CLAIM

The ornamental design for an electric vehicle charger as shown and described.

DESCRIPTION

FIG. 1 is a front view of an electric vehicle charger showing our new design;

FIG. 2 is a left side view of the electric vehicle charger of FIG. 1;

FIG. 3 is a back view of the electric vehicle charger of FIG. 1;

FIG. 4 is a top view of the electric vehicle charger of FIG. 1;

FIG. 5 is a bottom view of the electric vehicle charger of FIG. 1;

FIG. 6 is a right side view of the electric vehicle charger of FIG. 1;

FIG. 7 is a left side perspective view of the electric vehicle charger of FIG. 1; and,

FIG. 8 is a right side perspective view of the electric vehicle charger of FIG. 1.

The ornamental design which is claimed is shown in solid lines in the drawings. The broken lines of equal length dashes in the drawings depict portions of the electric vehicle charger that form no part of the claimed design.
